UNITED STATES PATENT OFFICE.

GEORGE D. PARKER, OF RIVERSIDE, CALIFORNIA.

RECEPTACLE-INVERTING MECHANISM.

1,210,096.

Specification of Letters Patent. Patented Dec. 26, 1916.

Application filed November 26, 1915. Serial No. 63,617.

To all whom it may concern:

Be it known that I, GEORGE D. PARKER, a citizen of the United States, residing at Riverside, in the county of Riverside and 5 State of California, have invented certain new and useful Improvements in Receptacle-Inverting Mechanisms, of which the following is a specification.

This invention relates to box elevating and 10 dumping machines, and more particularly to a type of apparatus wherein there is employed an elevator of the endless conveyer type for receiving the filled boxes, either singly or in stacks to elevate the same to be 15 acted on by the dumping or inverting mechanism; thus enabling a greater number of boxes to be handled than where a reciprocating conveyer is employed, and providing an apparatus wherein the attendant at the 20 elevator may be dispensed with, and the boxes in stacks are positioned by the truckmen within the sphere of the elevator and to be elevated and dumped thereby.

In box elevators and dumpers as at present 25 used, and wherein boxes in stacks are handled, a reciprocating elevator is employed to elevate the stack to the dumping means. In this structure the lowermost box of each stack is not dumped immediately following 30 the preceding boxes of the stack, but is retained in its elevated position and before the same is moved into the sphere of the dumping mechanism, it is necessary for the elevator to return to its lowermost position, re- 35 ceive another stack of boxes, the topmost box of this stack contacts with the elevated box of the preceding stack and raises it into the sphere of the dumping mechanism, and in this type of machine the elevator is never 40 clear and owing to its double movement is consequently slow in its operation.

The present invention has for its principal objects to provide an apparatus having an endless elevator whereby the filled boxes may 45 be moved into the path thereof to be engaged thereby, as soon as the elevated stack will clear the top of the next stack to be placed in position, thereby providing a continuous feed of boxes to the dumping mechanism; one provided with means for successively removing the uppermost filled box 50 from the stack and positioning the same within the sphere of the dumping or inverting mechanism and to be acted on thereby, and one which is simple in construction, has 55 an increased capacity over similar devices

now on the market, and one which may be manufactured at little cost.

While my present apparatus is designed for use in packing houses for elevating and 60 dumping the boxes containing the fruit to be treated and packed, it is to be understood that the same may be utilized wherever a receptacle elevator and dumper is necessary and may be constructed to elevate the receptacles to various heights. 65

With the above mentioned and other objects in view, the invention consists in the novel construction and combination of parts hereinafter described and illustrated in the 70 accompanying drawings; it being understood that various changes in the form, proportion, size and minor details of construction within the scope of the claims may be resorted to without departing from the spirit 75 or sacrificing any of the advantages of the invention.

To more fully comprehend the invention, attention is directed to the accompanying 80 drawings illustrating an elevator and dumper embodying my invention, and wherein—

Figure 1 is a view in front elevation, disclosing the endless elevator, the box dumping or inverting mechanism and the means 85 for removing the uppermost box of the stack and positioning the same in co-operation with the dumping mechanism. Fig. 2 is a view in side elevation, disclosing more fully the operating means for the various parts of the 90 apparatus. Fig. 3 is a sectional view taken on line 3—3 of Fig. 1, viewed in the direction of the arrows, disclosing more fully the mechanism for engaging the uppermost ele- 95 vated box and for positioning the same with- in the sphere of the dumping or inverting mechanism. Fig. 4 is a sectional view taken on line 4—4 of Fig. 1, disclosing more fully the endless elevator, the dumping mechanism carrying the box engaging pins, the belt for 100 receiving the dumped fruit, and the runway for conveying the empty box from the apparatus. Fig. 5 is a diagrammatic view in side elevation of the apparatus, disclosing a number of boxes and the cycle of operation 105 of the apparatus in dumping the contents therefrom. Fig. 6 is a sectional view taken on line 6—6 of Fig. 1, disclosing more fully the elevator and the box guides. Fig. 7 is a view in detail of one of the box supporting 110 pins carried by the end flanges or disks of the inverting mechanism.

In the drawings, 1 and 1^a indicate suitable frame uprights or standards resting on a base 2 and preferably extending upwardly through a loading station or floor 3, and 5 carrying at their upper ends the top frame members 4, the front uprights 1^a being rearwardly inclined, as in the drawings. Front and rear uprights 1 and 1^a are connected by braces 5, and braces 6 connect the front up- 10 rights 1^a.

To clearly set forth the elements and operation of the elevator and dumper or inverting mechanism, the endless elevator will first be described, and the same includes 15 suitable parallel spaced upwardly disposed side guides 7 secured to the braces 5 and extending from a point below the floor or loading platform 3 to a point adjacent the dumping or inverting means hereinafter described. Parallel spaced end guides 8 are secured to the braces 5 at the outer sides of the side guides 7 and the outer edges thereof project outwardly beyond the faces of the side guides. Suitable shafts 9 are rotatably 20 mounted in bearings at the upper and lower ends of the front uprights, and said shafts carry sprockets 10 over which operate the endless chains 11; see Figs. 1, 2, 3 and 4. Stack supports or elevating platforms A are 25 carried at suitable spaced points between the endless elevating chains 11, and the same comprise the supporting rods or shafts 12 fulcrumed at their ends in the chains 11 and connecting the same. At the opposite 30 ends of said members 12 are carried the rectangular brackets 13 connected at their upper outer ends by the bar 14. The brackets carry on their lower end the rollers 15, which, on the upward movement of the 35 platforms contact with the guide rails 16 carried by the braces 6 and extending upwardly between the side guides 7 and which terminate at their upper ends in the inwardly curved portions 17 which maintain 40 the platforms A substantially horizontal when in their highest elevated position. The lower ends 18 of the guide rails 16 are inwardly curved so as to properly receive the rollers 15 when the lower ends of the 45 brackets are unsupported. On the downward movement of the platforms the rollers 15 operate over guide rails 19, Fig. 4, over the top edges of which extend the upper ends of the side guides 7. The upper shafts 50 55 9 each carry a large sprocket 20 on which operates a chain 21 driven by a sprocket 22 carried by a shaft 23 mounted in bearings carried by the braces 5.

A suitable box inverting or dumping 60 mechanism is carried at the upper portion of the supporting frame above and to the rear of the stack elevator to successively receive the topmost box of the stack and gradually invert the same to dump the contents therefrom, and the same comprises a

supporting shaft 24 extending transversely of the top frame members 4 and journaled in bearings 25 carried thereby. Keyed to rotate with the shaft 24 are the spaced circular end disks or members 26 of a dumping 70 drum, and said disks are of a sufficient diameter and so arranged so as to overlap the elevator, and are positioned one on each outer side of the elevating chains 11. The peripheral edges of the disks are formed 75 with teeth and over the same operate drive chains 28 carried by sprockets 29 mounted on the shaft 23. A belt or runway 30 for receiving the fruit as dumped from the boxes extends over a drum or roller 31 80 loosely mounted on the shaft 24 between the members 26 and is inclined downwardly toward the rear of the frame where it operates over a drum 32 keyed to rotate with a power shaft 33 which is driven in the direction of 85 the arrow by any suitable power, transmitted to the band wheel 34. Parallel spaced tracks or guides 31' for receiving the inverted boxes extend longitudinally over the side edges of the belt 30 from a point 90 centrally of the drum 31, and are beveled as at 32' at their front end and are downwardly inclined toward the rear of the frame to convey the empty boxes from the inverting mechanism to any suitable place 95 of deposit.

The shaft 23 carries a large sprocket 35, and the same receives its power through a chain 36 operating on a sprocket carried by a shaft 37 which is in turn driven by a chain 100 38 operating over a sprocket 39 loosely carried by the power shaft 33. A clutch dog 40 is keyed to rotate with the shaft 33 and with the same is adapted to intermesh a dog 41 rotatable with the sprocket 39 and movable laterally relatively thereto into and out of engagement with the clutch dog 40. A controlling handle or lever 42, pivoted as at 43, co-operates with the dog 41 and assists in moving the same relatively to the dog 40. 110

A mechanism is employed for moving the uppermost box when the same is raised to its highest position by the elevator into operative relation with the inverting mechanism, and the same comprises the side frame members 44, slidably mounted in guides 45 fulcrumed adjacent their inner ends as at 46 to the top frame members 5 in advance of the shaft 24, and exteriorly of the disks or members 26. A bar 47 is adjustably united at its opposite ends, as at 47', to the outer ends of the members 44 and carries a roller 48 which extends transversely of the elevating mechanism and inverting mechanism. The adjustability of the roller relative to the frame members 44 admits of the raising or lowering of the roller to engage the elevated boxes adjacent the lower edge thereof and to compensate for boxes of various heights. At timed intervals the roller con- 115 120 125 130

tacts with the outer face of the highest elevated box to draw the same into coöperative relation with the inverting mechanism. The rear ends of the members 44 are pivotally connected by links 49 with the long members of crank arms 50 fulcrumed in brackets 51 carried by the braces 5. The short members of the crank arms carry idlers 52 which operate in cam slots 53 in cams 54 carried by the shaft 23—Figs. 3 and 4. The operation of the cams 54 causes the side frame members 44 carrying the roll 48 to reciprocate in the guides 45, and to draw the filled boxes from the elevator into coöperative relation with the inverting mechanism. The rear end of each guide 45 carries a roller 55 on which operates a four lobe cam 56, carried by the shaft 24.

The cams 54 and 56 are timed to operate in such a way as to raise the outer ends of the guides 45 as the engaging frame is projected outwardly, thence to permit the outer ends of the guides to lower with the engaging frame over the topmost box as the same is elevated to its highest position, and while in this position to engage the outer lower edge of the box and draw the frame inwardly carrying the topmost box from the stack into the path of the inverting mechanism. The filled boxes as successively removed from the elevator are caused to slide on and are supported by the upper ends of the guides 7 until between the disks or end members 26 of the inverting mechanism, at which time the lifting pins or fingers 57, slidably mounted in apertures adjacent the peripheral edges of the disks or end members, are forced inwardly by the cam tracks 53 carried by the frame and which operate in the grooved ends of the pins or fingers and engage beneath the under outer edge of the boxes.

When first received in the inverting mechanism the inner lower edge of the boxes contact with the pins or fingers 59 projecting inwardly from the disks or end members 26 adjacent the hub thereof and the upper inner edge of the boxes contact with the belt 30 around the drum 31. As the end members 26 are rotated and the boxes gradually assume an inverted position with the upper inner edges thereof in contact with the forward end of the guides 31', the contour of the cam tracks 58 successively withdraws the lifting pins or fingers 57 from under the bottom of the boxes and permits the same to pass beyond the boxes, as in Fig. 5. The boxes are now supported by the pins or fingers 59 until the rotation of the disks 60 or end members causes the pins or fingers 60, which are approximately on a radial line with the pins 59, to engage under the lower corners of the boxes and complete the dumping of the contents therefrom; and cause the boxes to assume an inverted posi-

tion on the tracks or guides 31'. The rotation of the disks 26 causes the pins 60 to pass downwardly over one side of the boxes when the same are inverted on the tracks 31', and move or push the same beyond the path thereof rearwardly on the tracks or guides 31'. Successively inverted boxes propel the previously inverted boxes longitudinally of the guides or tracks 31 until the same are discharged therefrom. Grooves 61 and 62 are provided in the outer side edges of the tracks or guides 31' for the passage of the respective pins or fingers 59 and 60.

I have provided a box elevator and dumper which comprises three essential elements, all operating in timed relation with each other, and they include an endless traveling elevator for raising either a single box or a stack of boxes, an inverting mechanism of the rotating type which receives the filled box and gradually inverts the same, dumping the contents therefrom onto one conveyer and depositing the dumped box onto suitable conveying tracks or rails, and a mechanism for removing the top box from the conveyer or stack of boxes and for positioning the same within the sphere or in coöperative relation with the inverting mechanism.

It will be noted that the elevator is of the endless type and during the operation of the apparatus travels continuously in the same direction, and also that the roller 48, during the reciprocation of the side members 44 and the raising and lowering of the guides 45, travels in an elliptical path, as in Fig. 5, to remove the upper box from the elevator into the sphere of the inverting mechanism.

Having thus described my invention, what I claim as new and desire to protect by Letters Patent is:—

1. An apparatus for the described purpose comprising an endless elevator for receiving and elevating filled receptacles, an inverting mechanism without the path of the elevated receptacles for receiving the filled receptacles from the elevating means and inverting the same to dump their contents therefrom, and means operating in timed relation with the elevating and the inverting mechanism for removing the uppermost receptacle from the elevator and placing the same within the sphere of the inverting mechanism.

2. An apparatus for the described purpose comprising an endless elevator for receiving and elevating filled receptacles, an inverting mechanism without the path of the elevated receptacles for receiving filled receptacles from the elevating means and inverting the same to dump the contents therefrom, means operating in timed relation with the elevator and the inverting

mechanism for removing the uppermost receptacle from the elevator and placing the same within the sphere of the inverting mechanism, means for conveying the inverted receptacles from the apparatus, and means for receiving the contents as dumped therefrom and for conveying the same from the apparatus.

3. An apparatus for the described purpose comprising an endless elevator for receiving and elevating filled receptacles, an inverting mechanism without the path of the elevated receptacles for receiving the filled receptacles from the elevating means and inverting the same to dump the contents therefrom, and reciprocating means operating in timed relation with the elevating and the inverting mechanism for engaging and moving the uppermost elevated receptacle within the sphere of the inverting mechanism.

4. An apparatus for the described purpose comprising an endless elevator for receiving and elevating filled receptacles, a rotating inverting mechanism without the path of the elevated receptacles for receiving the filled receptacles from the elevating means and inverting the same to dump the contents therefrom, and reciprocating means movable within the path of the receptacle elevating and operating in timed relation with the elevator and the inverting mechanism for engaging and moving the uppermost elevated receptacle to within the sphere of the inverting mechanism.

5. An apparatus for the described purpose comprising a rotary receptacle inverting mechanism for receiving filled receptacles and inverting the same to dump the contents therefrom, horizontally reciprocating means operating in timed relation with the rotary inverting mechanism for engaging a receptacle and moving the same into the sphere of the inverting mechanism, and upwardly movable means for positioning receptacles to be successively engaged by the receptacle moving means.

6. An apparatus for the described purpose comprising a receptacle inverting mechanism for receiving filled receptacles and inverting the same to dump the contents therefrom, substantially horizontally moving means operating in timed relation therewith for engaging and moving a receptacle therefrom to a point within the sphere of the inverting mechanism to be acted on thereby, and timely operated upwardly moving means for positioning receptacles to be successively engaged by the receptacle moving means.

7. An apparatus for the described purpose comprising a receptacle inverting mechanism for receiving filled receptacles and inverting the same to dump the contents therefrom, means operating in timed relation

therewith for engaging and moving a receptacle within the sphere of the inverting mechanism to be acted on thereby, timely operated continuously moving endless means for positioning receptacles to be successively engaged by the receptacle moving means, means for receiving the contents dumped from the inverted receptacles, and means on which the inverted receptacles are conveyed from the apparatus.

8. An apparatus for the described purpose comprising a receptacle inverting mechanism for receiving filled receptacles and inverting the same to dump the contents therefrom, means operating in timed relation therewith for engaging and moving a receptacle within the sphere of the inverting mechanism, and timely operated continuously moving endless means for positioning receptacles to be successively engaged by the receptacle moving means.

9. An apparatus for the described purpose, comprising a receptacle inverting mechanism for receiving filled receptacles and inverting the same to dump the contents therefrom, an endless conveyer for moving filled boxes in position adjacent to said inverting mechanism, and timely operated reciprocating means for engaging the positioned receptacles and moving the same to be acted on by the inverting mechanism.

10. An apparatus for the described purpose, comprising a receptacle inverting mechanism for receiving filled receptacles and inverting the same to dump the contents therefrom, an endless conveyer for moving filled boxes in position adjacent to said inverting mechanism, and a reciprocating open frame operated in timed relation relative to said inverting mechanism and movable in a substantially oval path for positioning over the positioned receptacles and moving the same toward the inverting mechanism, to be acted on thereby.

11. An apparatus for receiving filled receptacles and dumping the contents therefrom, the same comprising a rotary member for receiving, supporting and turning the receptacle to empty the contents therefrom, and horizontally reciprocating means coacting in timed relation therewith for moving receptacles successively within the sphere of the said rotatable dumping means.

12. An apparatus for receiving filled receptacles and dumping the contents therefrom, the same comprising a rotatably mounted member for receiving and supporting the receptacle and during the movement of which the receptacle is turned to empty the contents therefrom, and horizontally moving means coacting in timed relation therewith for moving receptacles successively within the sphere of the said rotatable dumping means.

13. An apparatus for the described purpose

comprising a receptacle elevator and a receptacle inverting mechanism associated therewith and without the path thereof, and means for moving the receptacles from the elevator into the sphere of the inverting mechanism, the elevator, inverting mechanism and receptacle moving means being operated in timed relation with each other.

In testimony whereof I have signed my name to this specification in the presence of 10 two subscribing witnesses.
